UNITED STATES PATENT OFFICE.

FRIDOLIN SCHIMMEL, OF FARIBAULT, MINNESOTA.

SANDPAPERING-MACHINE.

959,614.

Specification of Letters Patent. Patented May 31, 1910.

Application filed May 3, 1909. Serial No. 493,462.

To all whom it may concern:

Be it known that I, FRIDOLIN SCHIMMEL, a citizen of the United States, residing at Faribault, in the county of Rice and State 5 of Minnesota, have invented certain new and useful Improvements in Sandpapering-Machines; and I do hereby declare the following to be a full, clear, and exact description of the invention, such as will enable others 10 skilled in the art to which it appertains to make and use the same.

My invention has for its especial object to provide an improved sandpapering machine, and to this end, it consists of the novel 15 devices and combinations of devices herein-after described and defined in the claims.

Particularly, this invention is directed to the provision of improved means for applying pressure on a sandpaper belt or similar 20 belt used for smoothing or polishing wood or other materials. It provides a device for use in connection with a belt of this character, whereby instead of pressing a large surface of the belt at one time against the object 25 being sandpapered or polished, it will press the said belt only at one point or a small portion at a time, and this point may be shifted or caused to travel along the belt, and hence, from one place to another on the 30 board or material which is subject to the belt.

In the accompanying drawings which illustrate the invention, like characters indicate like parts throughout the several 35 views.

Referring to the drawings: Figure 1 is a view in front elevation, with some parts broken away, showing the sandpapering machine with my invention incorporated there- 40 in; Fig. 2 is an enlarged front elevation of the main body portion of the machine, the end portions thereof being broken off; Fig. 3 is a vertical section taken from front toward the rear of the machine on the line 45 $\alpha^3 \alpha^3$ of Fig. 2; and Fig. 4 is a plan view of the parts shown in Fig. 3.

The board which is indicated by the character Y, is shown as placed upon a suitable supporting table 1, which latter may be of 50 any suitable construction, such for instance, as that disclosed and claimed in the companion application, filed by me of date May 3rd, 1909, under S. N. 493,461, entitled "Vertically adjustable table." It may be

here stated that in Fig. 2, the part Y is 55 shown as a quite thick board, while in Fig. 1, it is shown as a very thin board or veneer.

The sandpaper or polishing belt 2 is ar- 60 ranged to run over pulleys 3, the shafts 4 of which are journaled in suitable bearings on a horizontally extended frame 5, which lat- 65 ter may be supported in any suitable way, but as shown, is suspended and rigidly held by hanger brackets 6, secured at their upper ends to beams of an overhead floor or ceil- 70 ing 7. One of the pulleys 3 will, in practice, be driven by suitable means forming no part of the present invention, and hence, not 75 illustrated.

A rocking supplemental frame shown as 70 made up of end brackets 8, an intermediate bracket 9, and a horizontally extended guide bar 10 is pivotally connected to the frame 5, as shown, by means of trunnions 11 on the 75 ends of the said bar 10, which are journaled in bearings 12 on the front face of said frame 5. In the upwardly extended portions of the brackets 8 and 9, a rock shaft 13 is journaled, and this rock shaft, at its intermediate portion, is provided with a beveled pinion 14 80 that meshes with a bevel gear 15, shown as journaled on a stud 16 of the intermediate bracket 9. This gear 15 is provided with a forwardly extended arm 17, that is arranged 85 to work between stop pins 18, adjustably 90 mounted in perforations 19 of a yoke-like bracket 20, the ends of the down-turned prongs of which are rigidly secured to the 95 back of the guide bar 10 of the oscillatory supplemental frame. The intermediate bracket 9 is provided with a rearwardly ex- 100 tended guide flange 9^a on which a counter- weight 21 is adjustably mounted. The pur- 105 pose of this counter-weight and also of the arm 17 above described, will appear in the description of the operation.

The rock shaft 13 is provided at intervals along its length, with short depending arms 22 that are set circumferentially one ahead of the other progressively from one end to- 100 ward the other of said rock shaft. The free ends of these arms 22 support a slightly spiral rod 23, on which, at points between the arms 22, presser rollers 24 are loosely journaled, but are held properly spaced 105 preferably by sleeves 25. These rollers, which in a broad sense, constitute plunger actuating tappets, are located with their axis

on a spiral line, but equi-distant from the axis of the rock shaft 13.

Located immediately below each presser roller 24, is a presser plunger 26. These 5 plungers 26 are arranged to work vertically through perforations in the forwardly projecting portion of the oscillatory frame bar 10, and at their lower ends, they are pivotally connected to a flexible presser bar 10 27, and are provided with forwardly and rearwardly projecting stop fingers 28 that permit slight transverse oscillatory movements of said presser bar in respect to the said plungers, as best shown in Fig. 3. At 15 their upper ends, the plungers 26 are provided with segmental heads 29 that are engaged each by one of the presser rollers 24. Leaf springs 30 attached at their rear ends to the rear portion of the oscillatory frame 20 bar 10, engage the respective heads 29 at their forwardly projecting free ends, and yieldingly press the respective plungers upward and maintain engagement between the heads 29 and the co-operating presser rollers 25 24. It is here important to note that after the presser rollers 24 are offset on a spiral or irregular line, the lower portions thereof 30 will always be at different altitudes, and will engage with different portions of the heads 29, so that the flexible presser bar 27, while nearly horizontal, is never truly horizontal, but is always bent on a curved or wave-like line with one point or small portion thereof always pressed below other 35 portions thereof. Obviously, the presser roller which is located with its axis vertically below the axis of the rock shaft 13, and hence, alined with the axis of the co-operating plunger 26, will press the under- 40 lying portion of the flexible presser bar 27 to its lower position. It is further obvious that by oscillatory movements of the arm 17, the rock shaft 13 may be oscillated, so as to throw any one of the several presser rollers 45 into its lower position. Furthermore, it is evident, that when the arm 17 is moved from one extreme position to another, the flexible presser bar 27 will be depressed with a wave-like action in which its lowermost portion 50 will travel from one end to the other. Of course, the said flexible presser bar may be given a lowermost depression at any desired point, by the proper manipulation of the said arm 17.

55 The lower portion of the belt 2, is, of course, arranged to move directly under the veneer or board Y, and directly over the flexible presser bar 27. Hence, by the above noted manipulation of the said presser bar, 60 a very delicate, yet highly efficient action of the belt, may be produced on the board, veneer or other article that is being smoothed or polished. The amount of pressure on the presser bar 27, and hence on the operative portion of the belt, may be varied by

adjustments of the counter-weight 21. A thin veneer will, of course, require much more delicate sandpapering action than a board or heavier strip. Fine veneer, such as used in making piano cases and in various 70 cabinet work, are very thin and expensive, and great care must be taken in sandpapering the same to prevent destruction thereof. Furthermore, it usually happens that a greater amount of dressing is required at 75 some points of the veneer than at others. The improved belt pressing device above described, is especially adapted for this kind of work.

It frequently happens that the article being sandpapered, is shorter than the presser bar 27, and to adapt the machine for this short work, without wasting time, the stop pins 18 are made adjustable so as to properly limit the movements of the arm 17. 80

The belt 2 may not in all cases be a sandpaper belt, and hence, it is herein treated broadly as a finishing belt.

In actual practice, this improved mechanism has been found highly efficient for the 90 purposes had in view.

What I claim is:

1. The combination with a finishing belt and guides therefor, of means for pressing the operative portion of said belt with a 95 wave-like action, comprising spirally arranged pressure controlling means and co-operating devices for transmitting the variable pressure therefrom to the said operative portion of the belt.

2. The combination with a finishing belt and guides therefor, of a flexible presser bar engageable with the operative portion of said belt, a rock shaft having spirally arranged tappets, and means for transmitting 105 the pressure from said tappets to said presser bar for imparting a wave-like belt-engaging movement thereto.

3. The combination with a finishing belt and guides therefor, of a flexible presser bar 110 overlying the operative portion of said belt, a multiplicity of independently movable plungers operative on said presser bar, and a rock shaft having spirally spaced tappets operative on said plungers, substantially as 115 described.

4. The combination with a finishing belt, of an oscillatory frame, a multiplicity of independently movable plungers mounted thereon, a rock shaft having spirally spaced 120 tappets operative on said plungers, and a flexible presser bar subject to said plungers, and arranged to act upon the operative portion of said belt, substantially as described.

5. The combination with a finishing belt 125 and guides therefor, of a pivoted frame having an adjustable counter-weight, a rock shaft having spirally spaced tappets, a multiplicity of plungers mounted on said frame and subject to said tappets, and a flexible 130

presser bar subject to said plungers, and arranged to act upon the operative portion of said belt.

6. The combination with a finishing belt 5 and guides therefor, of a pivoted frame, a multiplicity of independently movable plungers mounted thereon, a rock shaft having a multiplicity of spirally spaced presser wheels operative on the upper ends of said 10 plungers, and a flexible presser bar subject to said plungers and engageable with the operative portion of said belt, substantially as described.

7. The combination with a finishing belt 15 and guides therefor, of an oscillatory shaft having a multiplicity of spirally spaced tappets, a multiplicity of independently movable plungers subject to said tappets, and provided with connections for action on the 20 operative portion of said belt, and a lever for oscillating said shaft.

8. The combination with a finishing belt and guides therefor, of an oscillatory frame 25 gravity held in an operative position, a multiplicity of independently movable plungers mounted on said oscillatory frame, a flexible presser bar pivotally connected to

the lower ends of said plungers and arranged to engage the operative portion of said belt, and a rock shaft having spirally 30 spaced tappets operative on the upper ends of said plungers, the said plungers being yieldingly pressed upward.

9. The combination with a finishing belt and guides therefor, of an oscillatory frame 35 gravity held in an operative position, a multiplicity of plungers spring pressed upward and independently mounted on said frame, a flexible presser bar pivotally connected to the lower ends of said plungers, 40 said plungers having heads at their upper ends, a rock shaft mounted on said frame, and provided with spirally spaced presser wheels operative on the heads of said plungers, and a lever connected to said rock 45 shaft by inter-meshing gears, substantially as described.

In testimony whereof I affix my signature in presence of two witnesses.

FRIDOLIN SCHIMMEL.
